US00D502637S

(12) **United States Design Patent** (10) Patent No.: **US D502,637 S**
 Hattori et al. (45) Date of Patent: **** Mar. 8, 2005**

(54) **PORTABLE FASTENING MACHINE**

(75) Inventors: **Takeo Hattori**, Tokyo (JP); **Hiroshi Tanaka**, Tokyo (JP); **Satoshi Osuga**, Tokyo (JP)

(73) Assignee: **Max Co., Ltd.**, Tokyo (JP)

(**) Term: **14 Years**

(21) Appl. No.: **29/195,680**

(22) Filed: **Dec. 17, 2003**

(30) **Foreign Application Priority Data**

Jun. 25, 2003 (JP) 2003-018076
 Jun. 25, 2003 (JP) 2003-018079

(51) LOC (7) Cl. **08-05**

(57) **CLAIM**

The ornamental design for a portable fastening machine, as shown and described.

DESCRIPTION

FIG. 1 is a perspective view of front and left side of a portable fastening machine showing our new design;
 FIG. 2 is a front view thereof;
 FIG. 3 is a rear view thereof;
 FIG. 4 is a left side view thereof;
 FIG. 5 is a right side view thereof;
 FIG. 6 is a top plan view thereof; and,
 FIG. 7 is a bottom view thereof.
